UNITED STATES PATENT OFFICE.

GEORGE W. GOMBER, OF CONYNGHAM, PENNSYLVANIA, ASSIGNOR TO STANDARD AUTOMATIC MACHINE COMPANY, OF PITTSBURGH, PENNSYLVANIA, A CORPORATION OF DELAWARE.

VENDING MECHANISM.

1,297,677.

Specification of Letters Patent. Patented Mar. 18, 1919.

Application filed November 9, 1917. Serial No. 201,129.

To all whom it may concern:

Be it known that I, GEORGE W. GOMBER, a citizen of the United States, residing at Conyngham, in the county of Luzerne and 5 State of Pennsylvania, have invented a new and useful Vending Mechanism, of which the following is a specification.

This invention has reference to vending mechanism designed more particularly for 10 vending cigars, but capable of use for vending other articles. The object of the invention is to provide a mechanism, especially for vending cigars, wherein the liability of bunching or overrunning of the cigars is 15 avoided and but one cigar is released at a time on each operation of the mechanism.

The vending apparatus may be operated by coin-controlled mechanism such as shown and described in another application, Serial 20 No. 201,128, filed by me on even date here-with for coin-controlled mechanism for vending machines.

In accordance with the invention, the 25 cigars remain in the box, and the latter with the cigars is placed in the vending machine, one end of the box being removed, and the box is slanted or tipped in a manner to cause the cigars to gravitate through the open end of the box. In the path of the cigars there 30 are arranged associated belts so mounted that at each vending operation the belts are caused to reciprocate, thereby agitating and feeding the cigars toward the delivery end of the machine, this preventing either bunching 35 of the cigars or the feeding of the cigars more rapidly than intended.

Furthermore, holding devices are provided whereby but one cigar at a time can reach the discharge end of the machine.

40 The invention will be best understood from a consideration of the following detailed description, taken in connection with the accompanying drawings forming part of this specification, with the further understanding that, while the drawings show a 45 practical form of the invention, the latter is not confined to any strict conformity with the showing of the drawings but may be changed and modified so long as such 50 changes and modifications come within the scope of the appended claims.

In the drawings:

Figure 1 is a side elevation of so much of a vending machine as is necessary to illustrate the invention;

Fig. 2 is a longitudinal section about midway of the breadth of the vending portion of the machine;

Fig. 3 is a plan view of the structure shown in Fig. 2, with the casing in longitudinal section and some of the parts omitted;

Fig. 4 is a front end elevation of the structure shown in Fig. 2;

Fig. 5 is a section on the line 5—5 of Fig. 2.

Referring to the drawings, there is shown a vending apparatus A and a coin-controlled apparatus B, which latter, in its detailed construction, does not enter into the present invention but is shown and described in the 70 aforesaid application, and consequently no particular description of the coin-controlled part of the apparatus is given.

The structure A is provided with side walls 1 which may be made of sheet metal or otherwise constructed, and each side wall has a marginal flange 2 which may be attached to or form part of the side walls and serve to stiffen and strengthen the side walls. The walls 1 are secured together in spaced relation by rods or bars 3 at intervals, thus forming a sufficiently rigid sustaining structure for parts to be described. Extending diagonally upward from what may be termed the front end of the vending apparatus to the 80 rear end thereof is a partition or platform 4 designed to support a box of cigars. The shelf 4 has longitudinal slots 5 therethrough near its lower end and transverse slots 6 therethrough at higher points, the slots 6 being above a rod 7 mounted in and extending between the side walls 1. Mounted on the rod 7 so as to slide longitudinally thereon are brackets 8 each terminating at one end in an arm 9 rising through a corresponding slot 6 85 and carrying above the platform 4 a plate 10 constituting a clamp plate for holding a box of cigars so that when the box of cigars is resting on the platform 4, it is clamped between the two plates 10. To improve the clamping effect, each plate 10 has, at what constitutes its lower end, an upstanding wing 11 inset toward the other plate. On the rod 7 midway between the side walls 1 there is a stop member 12 held in place by a screw 13, from which latter there extend springs 14 to the brackets 8. The springs 14 hold the brackets against the stop members 12 but will yield to pressure applied to the plates 10 tending to 100 separate them.

Extending between and mounted in the plates 1 are shafts 15 and 16 and also extending between the sides 1 and mounted therein are other shafts 17 and 18. Secured to the shaft 15 on opposite sides of the longitudinal center line of the vending machine are segmental pulleys 19, each formed of an appropriately shaped piece of sheet metal made fast to the shaft 15 by screws 10 or otherwise. Secured to the shaft 16 by screws 21 are other segmental pulleys 22 corresponding to the pulleys 19 and of somewhat greater circumferential extent. The pulleys 19 are alined with the corresponding pulleys 22. Each pair of pulleys 19 and 22 carries a band 23 of webbing or other suitable flexible material, with one end provided with a reinforcement 24 having an opening whereby it may be secured over a screw or pin 25 on the pulley 19, while the other end of the band is made fast in a clip 26 engaged over the corresponding extremity of the pulley segment 22.

The shaft 17 carries pulley segments 27 and the shaft 18 carries pulley segments 28 beneath the shelf or partition 4, and these pulley segments carry belts or webs 29 similar to the webs 23 and similarly secured to the respective pulley segments. The arrangement is such that the belts 29 project through the longitudinal slots 5 and are arranged immediately beneath the belts 23, with the pulley segments 27 immediately under but spaced from the pulley segments 22.

The belts 23 are upright, and the belts 29 are nearly horizontal, sloping downwardly from that portion of the machine where the box of cigars is to be lodged so that the higher ends of the belts 29 underlie the open end of the box.

The shaft 15 projects through one side wall 1 and is there provided with a crank arm 30. The shaft 16 projects through the same side wall 1 and is there provided with a rock arm 31 extending on both sides of the axis of rocking. The arm 30 and one end of the arm 31 are connected together by a link 32, so that the two shafts rock simultaneously, and as the connected portions of the arms 30 and 31 are of the same length, these two shafts rock to the same extent.

The shaft 17 projects beyond the face plate 1 similarly to the shafts 15 and 16 and there carries a lever 33 having at one end an arm 34 in the path of which there is a pin 35 on the free end of a rock arm 36 carried by a shaft 37 mounted in and extending between the side plates 1, and also immediately over the pulley segments 22. Fast to the shaft 37 is a finger 38 having a terminal bent portion 39 shaped to engage and hold a cigar rolling down the partition or platform 4 near the discharge end thereof. At such discharge end the partition 4 is provided

with spaced slots 40 through which normally extend terminal portions 41 of angle arms or rods 42 carried at their other ends upon a shaft 43 extending between the side walls 1 and through the same side wall as the shaft 70 17, where the shaft 43 has fast thereto an arm 44 carrying at its free end a pin 45 in the path of an arm 46 extending from the lever 33 adjacent to its connection with the shaft 17. The shaft 43 has a pin 47 fast to 75 and projecting from it and connected to one end of a spring 48, the other end of which is secured to one of the side walls 1. The spring 48 tends to maintain the extremities 41 of the rods 42 projecting through the 80 slots 40 above the shelf 4 and in the path of any cigars which may move down the shelf toward the discharge end thereof.

The lever 33 has another arm 49 on the opposite side of the shaft 17 from the arm 34, and this arm 49 is connected by a link 50 to a bracket 51 on a push bar 52 forming part of the coin lock B and constituting the flexible operating member of the structure. The link 50, where connected to the 90 arm 49, has a loop 53 to constitute a lost motion connection.

That end of the arm 31 remote from the link 32 is connected by a link 54 to the arm 46, and the arm 36 is under the control of a 95 spring 55 connected to one of the walls 1.

The shafts 17 and 18 each have a pin 56 projecting from and fast thereto, and these pins are connected at their free ends by a link 57.

One of the rods 3 connecting the side walls 1 and located above and near the delivery end of the shelf 4 carries fingers 58 overriding that portion of the shelf over which cigars must travel from the box to the point 105 of delivery.

When the push bar 52 is operated from the position shown in Fig. 1, that is, when it is moved toward the left as viewed in Fig. 1, the lever 33 is rocked in a manner to carry the arm 34 toward the right, this movement rocking the shafts 15 and 16 clockwise and the shafts 17 and 18 also clockwise. The result of these movements is that the belt or web 23 moves downwardly and toward the left, while the belt 29 moves toward the right, both as viewed in Fig. 2. At the end of the movement, the arm 46 engages the pin 45, thus rocking the shaft 43 sufficiently to move the ends 41 of the arms or rods 42 out of the path of a cigar previously lodged against the ends 41, and the cigar promptly gravitates to the discharge end of the machine. The movements of the belts 23 and 29, which are in opposite directions so far as the cigars are concerned, tend to roll the cigars and thereby avoid any liability of the cigars clogging or jamming. The foremost cigar toward the discharge end can escape, but before this 130

occurs the release of the arm 36 by the arm 34 causes a movement of the finger 38 into the path of the released cigar, thus holding the latter from further movement so long as the ends 41 of the arms 42 are out of the path of the oncoming cigar. When the parts return to the first position, as occurs when the operating bar is released to move into the machine, the extremities 41 of the arms 42 reach a position to prevent the escape of the cigar before the cigar is released by the finger 38.

By providing one set of belts in an upright position and the other set of belts in a position approximating the horizontal, the cigars, with the exception of one or two about to be discharged, are free, and yet every time the device is operated all those cigars adjacent to the discharge end of the machine are agitated. The result of this is that any tendency of the cigars to jam or clog is prevented.

What is claimed is:

1. A vending machine for cigars and the like provided with reciprocatory agitating belts arranged at an angle one to the other, carriers for the belts, and lever and link connections between the carriers for causing movements thereof in timed relation.

2. A vending machine for cigars and the like provided with a shelf or partition having slots therethrough, belts extending through the slots, and rockable carriers for the belts, the shelf constituting a support for the cigars and the belts constituting agitating means for the cigars.

3. A vending machine for cigars and the like provided with associated reciprocatory agitating belts, each belt having a support comprising spaced pulley segments to which the belts are made fast at the ends of the segments remote from each other, and lever and link connections between the pulley segments.

4. A vending machine having feeding means for delivering the articles to be vended including spaced rock shafts, pulley segments on the shafts, belts connecting like pulley segments and fast thereto, and connections between the shafts for causing them to rock simultaneously to like extents.

5. A vending machine for cigars and the like provided with a shelf or partition having slots therethrough, rock shafts beneath and transversely of the shelf, pulley segments on the rock shafts registering with the slots, belts connecting the pulley segments and projecting through the slots, other shafts above the shelf transversely

thereof and located over corresponding ones of the first-named pulleys, and belts connecting the second-named pulleys and having substantially upright runs.

6. A vending machine for cigars and the like provided with a shelf or partition having slots therethrough, rock shafts beneath and transversely of the shelf, pulley segments on the rock shafts registering with the slots, belts connecting the pulley segments and projecting through the slots, other shafts above the shelf transversely thereof and located over corresponding ones of the first-named pulleys, and belts connecting the second-named pulleys and having substantially upright runs, and interconnections between the shafts for causing the first and second-named belts to reciprocate simultaneously in opposite directions.

7. A vending machine for cigars and the like provided with a portion along which the cigars may gravitate to the delivery end of the machine, reciprocatory stop means movable into and out of the path of the cigars approaching the discharge end of the machine, reciprocatory holding means movable into and out of the path of a cigar approaching the stop means, the holding means engaging the cigar when the stop means are withdrawn from such path, agitating means for the cigars for delivering them one at a time to the holding means, and operating means having connections to the agitating, stop and holding means for causing the operation of said means in timed relation to deliver the cigars one at a time.

8. A vending machine for cigars and the like having an inclined platform for supporting a box of cigars, rockable holding means for cigars, reciprocatory webs extending through the platform and having a like inclination, other reciprocatory webs in superposed spaced relation to the lower ends of the first-named webs and extending in an upright direction, and operating means for causing the reciprocation of the first and second-named webs in opposite directions, the release of a cigar held by the holding means, and the holding of the next cigar in order, the parts all being timed to operate in proper sequence.

In testimony, that I claim the foregoing as my own, I have hereto affixed my signature in the presence of two witnesses.

GEORGE W. GOMBER.
